UNITED STATES PATENT OFFICE.

HERMAN H. DIEHL, OF HUNTINGTON, WEST VIRGINIA, ASSIGNOR TO WEST VIRGINIA RAIL CO., OF HUNTINGTON, WEST VIRGINIA, A CORPORATION OF WEST VIRGINIA.

RAILWAY-TRACK CONSTRUCTION.

Application filed January 18, 1926. Serial No. 82,011.

My invention relates, more particularly, to the securing of rails to metal ties, especially in the case of track construction for use in mines, and general construction work; and more especially to structures comprising rail-flange-engaging clips rotatable on the ties and adapted to be rotated into and out of rail-flange-engaging position.

In the securing of the rails to the ties, it is customary for the clips to be rotated into the desired interlocking engagement with the rails, by the operator driving the clip to position by striking it at its outer end with a sledge, and the disengagement of the clips from the rail is also effected by hammering them out of place, it being one of my objects to provide a construction of clip which will readily stand heavy blows and afford a large surface against which the blows may be directed. A further object is to lessen the cost of manufacture of such clips and enhance the fit of the clip with the rail and tie.

Referring to the accompanying drawings:

Figure 1 is a plan view of a portion of a track-construction embodying my improvements, the tie forming a part thereof being broken away between its ends. Figure 2 is an enlarged section taken at the line 2 on Fig. 1 and viewed in the direction of the arrow. Figure 3 is an end view of the structure shown in Fig. 1, the structure being viewed from the right-hand side of Fig. 1. Figure 4 is a bottom plan view of one of the similar pivoted rail-flange-engaging clips, forming parts of the structure of the preceding figures. Figure 4^a is a longitudinal sectional view of the clip of Fig. 4, the section being taken at the line 4^a on Fig. 4 and viewed in the direction of the arrow. Figure 5 is a face view of a portion of a bar rolled into a form for producing clips of the construction shown in Fig. 4 and alternating therewith clips of another construction; and Figure 6 an edge view of the bar of Fig. 5.

In the particular, illustrated, embodiment of my invention, the tie is represented at 7 and the parallel rails superposed thereon at 8. The tie shown is of metal shaped to present parallel ribs 9 extending lengthwise of the tie, the side walls of the ribs 9, and represented at 10, being preferably relatively abrupt as shown. The tie is provided adjacent the inner flanges 11 of the rails, with

stationary abutments 12 which may be secured to the tie in any desirable way, as for example by the rivets 13, the edges of the abutments 12 adjacent the rails being undercut, as represented at 14, to provide portions 15 which overlap the inner flanges 11 of the rails. The tie adjacent the outer flanges 16 of the rails is provided with pivoted clips 17 for engaging the flanges 16 and cooperating with the abutments 12 for holding the rails in place on the tie. The clips 17 are all of the same construction each being pivoted between its ends to the tie, the pivoting means shown being an ordinary rivet 18 which extends through an opening 19 in the clip 17, preferably midway between its lateral edges and an opening 20 in one of the ribs 9 preferably midway between the lateral edges of the latter. The end of the clip 17 adjacent the rail is so shaped as to adapt it, when in rail-securing position, to overlap the flange of the rail with which it cooperates, as shown in Figs. 1 and 2, this being preferably accomplished by forming this end of the clip with an upwardly deflected portion represented at 21, and as a desirable means for gauging the rails and holding them from spreading, a depending lug 22 is formed on the portion 21 of the clip this lug engaging the outer edge of the flange 16 as shown. The lug 22 which extends only part way across the clip terminates at one side thereof in a depending flange 23. The end of the clip opposite that which overlaps the rail flange is provided on its underside at its longitudinal edges, with a pair of depending parallel ribs 24 spaced apart a distance equal to the width of the upper surface of the tie rib 9 as shown in Fig. 3, the provision of the ribs 24 causing the clip 17 to present a channel 25 along its underside. The outer end of the clip 17 and represented at 26 is very much thicker than the remainder of the clip, as represented, this portion of the clip gradually tapering toward the center thereof, and forming a portion against which the operator delivers the blows for turning the clip to interlocked, rail-flange-engaging position, the provision of the clip with this greatly thickened portion ensuring the striking of the clip by the workman and the driving of the clip to the position stated, without danger of impairing the clip.

The clip is preferably formed of steel

whereby it is caused to be springy, and the rivet 18 extends loosely through the clip, the parts being preferably so proportioned that the clip may freely rotate on the tie 5 when the rivet is in place thereon but when a rail is placed against adjacent abutment 12 it will require the application of considerable force to the clip in a direction for rotating it, and the flexing of the clip 10 against its inherent springiness, to rotate the clip from a position crosswise of the tie into a position in which it extends parallel with the ribs 9 and engages the rail, the flexing referred to occurring in the riding of the ribs 24 against the rib of the tie with which it cooperates, and the riding of the portion 21 against the inclined top surface of the rail flange 16, it being understood that when the clip reaches a position in which it extends parallel with the rib 9 its outer end 15 springs downwardly to receive this rib within the channel 25 of the clip, thereby locking the clip against accidental rotation out of rail-flange-engaging position. Furthermore, the parts are preferably so proportioned that the clip when in rail-flange-engaging position, as shown in Figs. 1, 2 and 3, will, under its spring action, bear down 20 at its opposite ends against the rail flange 25 and the tie respectively.

The clips 17 are preferably formed by rolling them from the desired metal in heated condition, to form long strips thereof which are afterwards cut into sections to 25 form the clips, following which operation the sections are preferably operated on by dies to flatten the clip at its thickened end and turn up the end 21 to ensure the flatwise engagement of the clip at its thickened 30 end with the tie and the passing of the end 21 of the clip into superposed position on the rail flange in the rotation of the clip on the tie. Inasmuch, however, as the clips 17 present the rather deep abrupt-shouldered portions 22, it is not possible to roll the bar with these portions of adjacent clips directly opposed, so that it is necessary to alternate these clips with clips having shoulder portions of relatively less depth, in order 35 to conserve the metal of the bar. In Figs. 5 and 6 I have illustrated a section of bar rolled to provide the clips just referred to, it being understood that this bar is rolled in any desired length. Before the bar is 40 passed through the rolls (not shown) for rolling it to the form illustrated, it is rolled into substantially rectangular cross-sectional form of a thickness slightly greater than the thickest portion of the end 26 of the clip and in such rolling is formed with flanges 45 extending throughout the length thereof at one face adjacent both of its outer edges, and which form the ribs 24 and lugs 23 in the completed clip, the one of said flanges

which is provided at the edge of the bar at 50 which the lugs 23 extend being somewhat deeper than the other of said flanges.

The dotted lines 27 indicate the points at 55 which the bar would be severed into clip-forming sections, as for example by a shearing operation, it being noted that alternate shearing lines extend midway between the ends of the flanges on the bar which in the finished clip are represented at 24, and that the other lines of shearing extend between 60 the lugs 22 and curved lugs 28 of the other type of clip produced from the bar, it being noted that as the lugs 28 are relatively shallow no difficulty will be encountered in rolling these lugs, these shallow lug clips while 65 forming no part of the construction shown in Figs., 1 to 4^a, inclusive, being useful for application to ties for holding rails down at the inside flanges thereof, the ties being provided with any suitable form of gauging 70 abutments at the outer flanges of the rails.

It will be understood from the foregoing 75 that a clip in accordance with my invention is very satisfactory in use and presents the desired strength to resist the various stresses 80 to which it is subjected.

While I have illustrated and described 85 a particular construction of clip and a particular method by which it is manufactured, I do not wish to be understood as intending 90 to limit it thereto as various changes and alterations may be made in the structure, without departing from the spirit of my invention.

What I claim as new, and desire to secure 95 by Letters Patent, is:

1. In combination with a tie, a rail-flange-engaging clip pivoted thereon and having a rail-flange-engaging portion at one end, its 100 opposite end being thickened relative to, and tapered toward, the center portion of the clip to provide a broad striking surface.

2. In combination with a tie, a rail-flange-engaging clip pivoted thereon and having a rail-flange-engaging portion at one end, its 105 opposite end being rolled to cause it to be appreciably thicker than the central portion of the clip.

3. In track construction, the combination 110 of a tie presenting upwardly-extending, relatively abrupt, surfaces spaced apart, and a clip, having a rail-flange-engaging portion pivoted between its ends on said tie and rotatable thereon about its pivot and presenting 115 downwardly-extending, relatively abrupt, surfaces spaced apart, the said surfaces on said tie and clip interlockingly engaging when said clip is in rail-flange-engaging 120 position, the portion of said clip presenting 125 said relatively abrupt surfaces being thickened relative to, and tapering toward, the central portion of the clip.

HERMAN H. DIEHL.
